UNITED STATES PATENT OFFICE.

WILLIAM GLEASON, OF RAHWAY, NEW JERSEY.

FLUSHING APPARATUS.

1,240,132.

Specification of Letters Patent. Patented Sept. 11, 1917.

Application filed April 14, 1917. Serial No. 162,111.

To all whom it may concern:

Be it known that I, WILLIAM GLEASON, a citizen of the United States, residing at Rahway, in the county of Union and State 5 of New Jersey, have invented new and useful Improvements in Flushing Apparatus, of which the following is a specification.

This invention relates to flushing apparatus for bath tubs, stationary wash tubs, sinks, basins, and like receptacles, and has 10 for one of its objects the provision of such an apparatus by means of which the drains of the receptacles may be freed from accumulations when they become clogged.

Another and more specific object of the 15 invention is to provide a flushing apparatus having a hollow plug for securement in the waste pipe or discharge opening of the receptacle, the plug being connected with a 20 flexible pipe or tubing for attachment to a faucet.

Another object of the invention is to provide in a flushing apparatus, an arm pivotally and removably connected to the hollow 25 plug and a closure for the overflow pipe, said closure being slidably and removably connected with the arm.

The invention also aims to generally improve flushing apparatus of this nature to 30 render it more practical, useful and commercially desirable.

With these and other objects in view as 35 will become more apparent as the description proceeds, the invention consists in certain novel features of construction, combination and arrangement of parts as will be hereinafter fully described, illustrated and claimed.

In the drawings, 40 Figure 1 is a fragmentary longitudinal sectional view through a bath tub showing my flushing apparatus mounted in operative position thereon.

Fig. 2 is a detail perspective view of the 45 apparatus removed from the tub, and showing the connection between the arm and the hollow plug.

Referring in detail to the drawings by 50 numerals, 1 designates as an entirety a bath tub of common construction having the waste or drain pipe 2 which communicates at its upper end with the tub through the bottom thereof. An overflow pipe 3 connects at its lower end with the waste pipe 2 below 55 the bottom of the tub and is in communica-

tion at its upper end with the interior of the tub slightly below the top thereof. 4 designates a faucet and 5 the water supply pipe therefor. It often happens that the waste or drain pipe 2 becomes clogged with 60 accumulations and extraneous matter of various descriptions and it is for the purpose of freeing this pipe, that I have provided my improved flushing apparatus.

The apparatus in its preferred construction comprises a hollow plug 6 having a central opening 7 in which is connected one end of a flexible pipe or tubing 8, the other end thereof being adapted for securement to the faucet 4 as shown. The flexible tubing 70 65 may be permanently connected to the plug 6 but has a removable connection with the faucet 4, it being merely slipped over the nozzle thereof when desired, and removed therefrom when not in use.

An arm 9 in the form of a metallic rod bent at its upper end into a handle forming loop 10 is provided for removable and pivotal attachment to the plug 6. The connection is formed by extending the lower end 80 of the arm at right angles to the main portion thereof to provide a tongue 11 which may be slipped into the socket opening 12 formed by the socket or cross over plate 13. This plate has the substantially U shaped 85 central portion 14 and the attaching flanges 15 which are secured by suitable fasteners 16 to the plug. The tongue fits rather loosely within the socket so that it may be rocked therein and tilted slightly with respect to its longitudinal axis.

A closure plug or disk 17 is provided for the intake end of the overflow pipe 3 and this plug is connected centrally of its outer face to a rod or arm 18 bent at one end to 95 form an eye 19 through which the arm 9 extends. The arm 18 has a sliding connection with the arm 9 and may be disconnected therefrom when it is desired to fold the apparatus into very compact form.

In use, the plug 6 is inserted into the intake end of the drain pipe 2 and the flexible tubing 8 connected to the faucet 4. The arm 18 is then connected with the arm 19 and the latter connected with the plug. 105 Now by pressing downwardly on the arm 9 by means of the handle loop 10, the plug 6 may be held firmly in position and by swinging the arm 9 about its pivotal end toward the overflow pipe, the overflow 110

closure 17 may be clamped in operative position to prevent any water which may back up into the pipe from flowing into the tub.

- From the foregoing description taken in connection with the accompanying drawings, it will be seen that I have provided a very simple and practical flushing apparatus, which may be cheaply manufactured to sell at a relatively low price, which may 5
10 be quickly assembled and applied to a tub or other receptacle to free the drain pipe of accumulations and which may be disassembled and arranged in compact form for storing or shipping.
- 15 While I have shown and described the preferred embodiments of my invention, it will be clearly understood that I do not wish to be limited to this construction, but may 20 make such changes as will fall within the scope and spirit of the invention as claimed.

What I claim is:—

1. In a flushing apparatus, a plug, means for conducting water through said plug, an arm having a handle formed on one end and

a lateral tongue formed on the other end, a 25 socket secured to the plug in which said tongue is removably fitted for locking movement, a second arm slidable on said first mentioned arm and detachable therefrom, and a closure carried by the second arm. 30

2. In a flushing apparatus, a plug adapted to fit into the drain pipe of a receptacle, a socket carried by said plug, an arm, a tongue formed on the lower end of said arm at right angles thereto, said tongue being adapted 35 for rocking and tilting movements within said socket, a second arm having an eye formed on one end through which the first mentioned arm extends, the second mentioned arm being slidable on the first mentioned arm and removable therefrom and a closure on the second mentioned arm adapted to be held by pressure from the first mentioned arm over the entrance to an overflow pipe. 40

45 In testimony whereof I affix my signature.

WILLIAM GLEASON.
